HANGER

Arthur L. Bissonnette, 5566 Waneta Drive, and Donald L. Stull, 5538 Waneta Drive, both of Dallas, Tex.

Filed Jan. 21, 1965, Ser. No. 83,502

Term of patent 14 years

(Cl. D80—8)

FIG. 1 is an elevational view of a hanger embodying our new design;

FIG. 2 is a cross-sectional view taken on line 2—2 of FIG. 1;

FIG. 3 is a cross-sectional view taken on line 3—3 of FIG. 1;

FIG. 4 is a cross-sectional view taken on line 4—4 of FIG. 1;

FIG. 5 is a cross-sectional view taken on line 5—5 of FIG. 1;

FIG. 6 is a cross-sectional view taken on line 6—6 of FIG. 1; and

FIG. 7 is an enlarged fragmentary elevational view of the portion of one arm in area 7 of FIG. 1.

We claim:

The ornamental design for a hanger, as shown.
